CLAIM

We claim the ornamental design for a stuffed toy dragon with detachable appendages, as shown and described.

DESCRIPTION

FIG. 1 is a front left perspective view of a stuffed toy dragon with detachable appendages, shown with appendages attached, showing the new design;

FIG. 2 shows a front elevation view thereof;

FIG. 3 shows a back elevation view thereof;

FIG. 4 shows a side elevation view thereof;

FIG. 5 shows a top plan view thereof; and,

FIG. 6 shows a bottom plan view thereof.

In the FIGS. 1-6, the broken line illustration of the environmental structure forms no part of the claimed invention.
